H. P. GONSOULAND,
WATER HEATING APPARATUS,
APPLICATION FILED DEC. 31, 1915.

1,198,344.

Patented Sept. 12, 1916.

UNITED STATES PATENT OFFICE.

HENRY P. GONSOULAND, OF OAKLAND, CALIFORNIA.

WATER-HEATING APPARATUS.

1,198,344.

Specification of Letters Patent. Patented Sept. 12, 1916.

Application filed December 31, 1915. Serial No. 69,656.

To all whom it may concern:

Be it known that I, HENRY P. GONSOULAND, a citizen of the United States, residing at Oakland, in the county of Alameda and State of California, have invented certain new and useful Improvements in Water-Heating Apparatus; and I do hereby declare the following to be a full, clear, and exact description of the invention, such as will enable others skilled in the art to which it appertains to make and use the same.

An object of this invention is to improve the construction of water heating apparatus, shown in my application for Letters Patent of November 2, 1914, Serial No. 869,966, so that the same can be used by connecting the steam feed pipe with the interior of the heater by means of a pipe, by means of which the steam can enter the heater and mix with the water contained therein, and further providing the heater with an outlet, which communicates with the journal boxes for the car axle, whereby to effect a cooling medium for the journal. A further object of this improvement is that, it may be employed as a fire extinguisher to cars when desired, by removing the hose from the reel and training the nozzle upon any desired point of the car which may be on fire.

With these and other objects in view as will become more apparent as the description proceeds, the invention consists in certain novel features of construction and arrangement of parts as will be hereinafter more fully described and claimed.

For a complete understanding of my invention, reference is to be had to the following description and accompanying drawing, in which the figure is a view in elevation and partly in section of a water heating apparatus made in accordance with this invention.

Referring to the drawing, the numeral 1 designates the water tank and 2 is the pipe which leads ordinary cold water into said tank. Leading from the tank 1 is a discharge pipe 3 which communicates with a water heater 4. The water heater 4 has a steam inlet pipe 5 with a valve 6, said pipe 5 leading into the heater 4 and connected up to a coil 7 extending from near the top to near the bottom of said heater, and terminating in a return pipe 8 which leads to the boiler of a locomotive. In the heater 4 is a float 9 secured centrally to a rod 10,

the upper portion 11 of which is adapted to slide in the pipe 3, and the lower portion 12 of which is adapted to slide in a pipe 13 which leads to the toilet bowl 14. The top and bottom walls of the heater 4 are formed to provide valve seats 15 and 16 respectively. The portion 11 is provided at a point above the float 9 with a valve 17, and the portion 12 is provided at a point 65 below the float 9 with a valve 19.

On the end of the heater 4, a hot water pipe 20, having a vertical pipe 21 and a horizontal pipe 22, leads up to a vertical pipe 23 to a faucet 24 disposed above the wash bowl 25, said faucet 24 being provided with a valve 26. The bowl 25 is provided with a waste pipe 27 which leads to the toilet bowl 14. The pipe 13 is provided with a flushing valve 28. Steam may be admitted 75 through the coil 7 through the steam pipe 5 to heat the water which is discharged into the heater 4 through the pipe 3 leading from the tank 1. When the water in the heater 4 rises to a certain height, the float 9 will 80 seat the valve 17 and unseat the valve 16, cutting off the supply of water to the heater and permitting the heated water to flow to the bowl 14 by the opening of the valve 28. When the level of water in the container 85 falls below a certain height, the float 9 will seat the valve 16 and unseat the valve 17, permitting water to enter the heater 4. The steam coil 7 will heat the water and it may be used in the wash bowl 25 and for flushing 90 the bowl 14.

Secured to the steam pipe 5, is a pipe 29, having a valve 30 therein and communicating with the heater 4 at the top thereof. By turning the valve 30 to an open position, 95 steam will enter the heater 4 and mix with the water therein and pass outwardly through the pipe 20. Secured to the pipe 21 is a horizontal branch pipe 31, having external screw-threads 32 on the outer end 100 thereof to receive a hose 33 which is wound upon a suitable reel 34. The free end of the hose 33 is provided with a nozzle 35 which may be passed through an opening 36 of the car floor and positioned within a journal box 105 which has become over heated, and by turning the valve 37 in the pipe 31 to an open position, steam and heated water combined may be played upon the journal box and reduce the degree of heat to a certain point 110 and then by closing the valve 30 the steam will be cut off and the heated water in the

heater 4 may be placed in the journal box to further reduce the degree of heat. If the journal box is not sufficiently cool the valve 6 may be closed, cutting off the steam to the 6 coil 7 and cold water from the tank 1, then will pass through the heater 4 to the pipe 31 and through the hose 33 to the journal box cooling said journal box to a medium degree of heat. The hose 33 may be em-
ployed as a fire extinguisher by removing it from the reel 34 and conveying it to any desired point of the car which may be on fire.

Secured to the waste pipe 27 is a drain pipe 38 communicating with a water cooler 39 of any desired type for conducting waste water from the water cooler 39 to the waste pipe 27 for further flushing the toilet bowl 14. A drip pan 40 to catch waste water 20 from the faucet 42 is connected with the drain pipe 38 by a pipe 41.

While I have shown and described the preferred embodiment of my invention, it will be understood that minor changes in 25 construction, combination and arrangement of parts may be made without departing from the spirit and scope of the invention as claimed.

What I claim is:—

30 1. A journal box cooler comprising a water tank, a heater connected to said tank, a steam pipe connected to said heater for heating water therein and mixing steam

therewith, an outlet pipe connected to the heater, a branch pipe secured to the outlet 35 pipe and provided with a valve therein for controlling the fluid therefrom, a hose connected to said branch pipe and bound upon a reel, the free end of said hose adapted to be inserted in a journal box to convey steam 40 and heated water from the heater to the journal box.

2. A combined water heater and journal box cooler, comprising a water tank, a heater connected to said tank, a steam pipe 45 connected to said heater and coiled therein, a return pipe connected to said coiled end of the steam pipe, means for controlling water to said heater, a pipe connected to the steam pipe and to the top of the heater, 50 a valve secured within the said pipe for controlling steam to the heater for mixing with the water therein, a valve secured within the steam pipe for controlling the steam to the coil, an outlet pipe connected 55 to said heater, a branch pipe connected to said outlet pipe, and a hose connected to said branch pipe for conveying combined hot water and steam or cold water to a journal box as desired.

In testimony whereof I affix my signature in presence of two witnesses.

HENRY P. GONSOULAND.

Witnesses:

WALTER MONTGOMERY,
JOSEPH PANELLA.
